UNITED STATES PATENT OFFICE.

GEORGE FINN, OF NEWARK, NEW JERSEY.

DESIGN FOR A SELF-HEATING SAD-IRON.

46,277.

Specification for Design.

Patented Aug. 18, 1914.

Application filed May 29, 1914. Serial No. 841,926. Term of patent 14 years.

To all whom it may concern:

Be it known that I, GEORGE FINN, a citizen of the United States, residing at Newark, in the county of Essex and State of New Jersey, have invented a new, original, and ornamental Design for a Self-Heating Sad-Iron, of which the following is a specification, reference being had to the accompanying drawing, forming a part thereof, and presenting a perspective view

of a self-heating sad iron embodying my design.

I claim:

The ornamental design for a self-heating sad iron, as shown.

GEORGE FINN.

Witnesses:

ARTHUR MARION,
CHAS. C. GILL.
